CLOSURE FOR CONTAINERS

Brent F. Cahoon, Kew Gardens, N. Y., and Howard C. Seaman, Jr., Short Hills, N. J., assignors of one-half to Armstrong Cork Company, a corporation of Pennsylvania, and one-half to Captive Closures, Inc., New York, N. Y., a corporation of Delaware

Application July 13, 1934, Serial No. 734,904

19 Claims. (Cl. 215—7)

This invention relates to closures for containers.

It has been found that with ordinary closures, purchasers of various products, particularly liquors, cannot be sure that they are getting the legitimate product for the reason that the contents of the bottle or other container are often tampered with between the packaging source and the consumer. Various ways of preventing this illicit tampering have been attempted but, for one reason or another, they have not proved entirely satisfactory.

It is an object of the present invention to provide simple and effective means for closing bottles and other containers such that the contents cannot be tampered with, at least without the fact of such tampering being made evident.

It is a further object of the invention to provide closure means for containers such that the container is initially hermetically sealed, such seal being readily and quickly broken when it is desired to use the contents.

It is a still further object of the invention to provide a closure for containers having improved means for sealing a once opened container against leakage.

With these and other objects in view, the invention consists in the features, combinations, details of construction and arrangements of parts which will first be described in connection with the accompanying drawings and then more particularly pointed out.

In the drawings:

Fig. 1 is a vertical sectional view of a container and its closure constructed in accordance with the invention, showing the parts in initial position;

Fig. 2 is a similar view, showing the parts after initial closing movement of the cap;

Fig. 3 is a similar view, showing the parts with the cap in open position subsequent to initial closing;

Fig. 4 is a perspective view, with parts broken away, of the parts shown in Fig. 2, but with the cap omitted for illustrative purposes;

Fig. 5 is a top plan view, with the cap omitted and prior to initial closing movement of the cap;

Fig. 6 is a sectional view of the ultimate cap;

Fig. 7 is a view, partly in vertical section and partly in elevation, of a modification, showing the parts in initial position;

Fig. 8 is a sectional view of the same, showing the parts after initial closing movement of the cap;

Fig. 9 is a perspective view of one of the parts prior to initial assembly;

Fig. 10 is a perspective view of another part;

Fig. 11 is a sectional view showing the cap of Fig. 7 on a different section line; and

Fig. 12 is a sectional view of a further modification.

Referring to the drawings, and more particularly to Figs. 1-6, there is provided a container and an initially imperforate end closure for initially completely closing and sealing the mouth of the container, this end closure having a frangible portion which is subsequently punctured to permit discharge of the container contents.

As here shown as an example, a container, such as a bottle 21, has a neck 22 provided with a thread 23. At the mouth of the bottle is the usual locking ring 24 such as is commonly provided for securing crown corks and other well known closures.

While the initial end closure and its frangible portion may vary in construction and arrangement, in the present exemplification it is part of an attachment which also performs other functions hereinafter referred to. To this end, the attachment comprises a ring-like body portion 25 surrounding the mouth of the bottle. Extending inwardly from body portion 25 is a clamping flange 26 overlapping the lip of the bottle. To prevent leakage between the bottle and the attachment a gasket 27 of cork or other suitable material may be interposed between flange 26 and the bottle lip. From the flange 26, the wall of the attachment has an upstanding portion 28. Inside the latter is a relatively horizontal frangible annulus 29 and inside that is a conical plug or valve element 30 hereinafter referred to. Below body portion 25 is an inwardly extending bend 31 which takes under the shoulder of the bottle locking ring 24. It will now be apparent that this bend and the clamping flange 26 serve to secure the attachment to the bottle. In the present exemplification, the bend 31 is formed by spinning the metal of the attachment in under the locking ring shoulder.

In carrying out the invention to what is now considered the best advantage, the frangible portion of the initial end closure is arranged to be disrupted over a predetermined area. This may be accomplished, for example, by weakening the wall of the end closure in such a manner that a given area of metal is broken away. In the exemplification illustrated in Figs. 1-6 the attachment which comprises the end closure is formed of so-called sheet metal and the weakening is con-

veniently accomplished by scoring the annulus 29 to define the area or areas to be broken away. To this end, and as shown more clearly in Figs. 1 and 5, the annulus 29 has four weakened portions. Each area 33 to be broken away is defined by an end scoring 34 and two side scorings 35, 36. There is no scoring at the remaining end in order that the metal will be disrupted in the form of tongues which remain rooted to the annulus, whereby no metal is allowed to drop into the container.

The invention in its entirety includes a cap for the container, axially movable on the container neck, and means for causing the frangible portion of the end closure to be broken away upon the initial movement of the cap into full closed position. Although capable of various constructions, in that illustrated as an example in Figs. 1-6, a cup-shaped cap 37 telescopes the bottle mouth and has an internal thread 38 engaging the bottle thread 23. This cap may conveniently be formed of molded plastic material. Extending downwardly from the top of the cap are one or more puncturing elements or breakers 39, the number depending upon the number of areas in the end closure that are to be broken away. In the present instance there are four such areas and four breakers.

With reference to the direction of rotation of the cap in approaching closed position, the leading face of each breaker 39 is slightly rounded and is V-shaped at the bottom to provide a piercing or breaking point. As appears more clearly in Fig. 6, each breaker recedes, toward the trailing end, to a vanishing point, to enable the cap to be removed from the manufacturing mold.

The invention in its entirety includes means for initially assembling the attachment in a predetermined angular position and for subsequently preventing relative angular movement of the attachment, thereby to insure the breakers and the weakened areas of the diaphragm having the proper relative position. While this may be accomplished in various ways, in the embodiment here shown as an example, the locking ring 24 has a vertical groove 42 and the body portion 25 of the attachment has a struck-in nib 43 which takes into the groove 42 (Fig. 4).

With this construction, the attachment may be initially assembled in a predetermined angular position on the bottle mouth and is thereafter locked in such position. In this way, the breakers are properly positioned with respect to the weakened areas. In the present embodiment, as will be more apparent hereinafter, it is desired that the puncturing operation end with the cap in full closed position. Consequently, the attachment is given such a position that when the cap is sufficiently short of full closed position to enable the puncturing operation to be completed during final movement, the advance points of the breakers are just about to engage the end scorings of the weakened areas.

After the bottle has been filled and the initial end closure attached, the cap is assembled but is screwed down only part way toward full closed position, namely, sufficiently to engage the threads but short of a point where the breakers will engage the frangible areas. This position is illustrated in Fig. 1. With the parts in this relation, which may be termed the initial condition, the package may be shipped, stored or the like without danger of leakage or deterioration of the contents since the container mouth is entirely closed and hermetically sealed. At the same time, the

existence of this unbroken end closure prevents tampering with the contents.

When it is desired to use the contents, the cap is screwed down to full closed position. During this combined rotary and axial movement of the cap, the leading ends of the puncturing elements 39 are forced against weakened areas 33 and cause the same to be broken away along the scored lines. The displaced metal rolls or curls up ahead of the breakers in the form of tongues which remain rooted integrally to the annulus 29 (Fig. 2). This piercing or breaking away results in the formation of a plurality of ports or passages 44 through which the bottle contents may thereafter flow (Fig. 3).

The invention in its entirety includes a cap having a discharge port and a valve element carried by the container neck for closing said port in one position of the cap. As here shown as an example, centrally located in the top of the cap 37 is a 20 conical discharge port or passage 45 (Fig. 3). When the cap is screwed down to closed position this port is closed and sealed by the conical valve element or plug 30 above referred to (Fig. 2).

The invention in its entirety includes means for 25 indicating to a purchaser or user whether or not the cap has been given the predetermined movement necessary to puncture the initial end closure. This may conveniently be accomplished by means operable upon said predetermined movement for altering the external appearance of the cap. Although capable of various constructions, in the embodiment illustrated as an example in Figs. 1-5, the cap discharge port 45 is initially 30 closed by an integral web 46 which may conveniently be the molder's flash. This web, at the top, is flush with the top of the cap so as to present a neat appearance. In order to insure an easy break-out of the web, its wall is made as thin as practicable around the edge thereof, as appears at 35 47 (Fig. 1). In this particular embodiment the valve element or plug 30 is utilized to break out the web. As previously described, the initial end closure is punctured when the cap is first screwed down to closed position. It has also been stated 40 that in closed position of the cap, discharge port 45 is closed by plug 30. It will be apparent, therefore, that the predetermined movement of the cap that causes the end closure to be punctured also causes the web 46 to be broken out, thus 45 altering the external appearance of the cap and indicating that the puncturing movement has taken place. Fig. 2 illustrates the parts at the end of this initial closing movement of the cap with web 46 just broken out. With the construction described, the web breaks out with a clean cut leaving a completed discharge port. It will be understood that the web drops away and is discarded.

The invention in its entirety includes means 60 for preventing complete removal of the cap and such means will advantageously be inaccessible. Although capable of various constructions, the locking means here shown as an example comprises a downwardly and outwardly extending 65 locking flange 50. This flange is of flexible and resilient material, e. g. metal, and is formed as part of the attachment previously described. As appears in the drawings (Figs. 1-5), the attachment has a V-shaped bend taking under the 70 shoulder of the bottle locking ring 24, the lower leg of the V constituting the locking flange 50. Cooperating with this flange is a bead 51 formed on the inner wall of the cap, above the thread, and in a position to be below flange 50 when the 75

cap is assembled on the container. This bead provides an upwardly facing shoulder the inner diameter of which is slightly less than the normal diameter of the rim of flange 50. Above bead 51 is a recess 52 to accommodate the flange 50 during opening and closing movements of the cap.

In the initial assembly of the cap onto the bottle neck, the thread crests and the bead 51 ratchet over the edge of flange 50 which yields or flexes inwardly. Once the bead 51 has passed, the flange springs back to approximately its initial position. Thereafter, it serves as a locking abutment, cooperating with bead 51 to prevent removal of the cap. That is, upon a given upward movement of the cap, bead 51 engages the rim of flange 50, as appears in Fig. 3, whereby further movement is prevented. If desired, flange 50 may be split to facilitate its flexibility.

In carrying out the invention in its entirety, provision is made for sealing the container mouth in closed position of the cap, once the package has been opened, this sealing being designed to prevent leakage not only through the discharge port but also down through the thread. This may be accomplished, in connection with plug 30, by effecting a seal outside the ultimate passages in the initial end closure. Although capable of various constructions, in the exemplification of Figs. 1-6 the cap is provided with a shoulder 53. Secured to this shoulder in any suitable manner is a sealing gasket 54 of cork or other suitable material. When the cap is in closed position (Fig. 2), the discharge port 45 is closed and sealed by plug 30 and gasket 54 is compressed against clamping flange 26 to prevent leakage down the thread.

To review the operation: after the bottle is filled the attachment comprising the initial end closure is assembled on the bottle mouth, the proper angular position being determined by the engagement of nib 43 in groove 42 (Fig. 4). Then the skirt of the attachment is spun in under the bottle locking ring 24 and the end of the skirt is flared outwardly to form the locking flange 50. Finally, the cap 37 is assembled on the container, the bead 51 and thread crests ratcheting over the edge of flange 50. The cap and bottle threads are caused to inter-engage but the cap is screwed down only part way towards full closed position, being stopped before the breakers 39 engage the frangible portion of the end closure. The package remains in this condition until the user desires to discharge the contents.

With the construction described, the package is tamper-proof in the sense that no tampering is possible without the fact of such tampering being made evident. Since the same movement that breaks the initial end closure also breaks away web 46, the purchaser or user can tell at a glance whether or not the package is in its original condition. That is, if the top of the cap presents an unbroken surface, the purchaser knows that the contents are still sealed by the initial end closure and that there can have been no tampering. If, on the other hand, the cap has a port in its top face, the purchaser knows that the cap must have been so moved as to break the initial closure and he is thereby put on notice that there may have been tampering. With the construction described, moreover, the above mentioned indication cannot be avoided by removing the cap, puncturing or removing the initial closure, and replacing the cap with web 46 intact

because the cap is locked against removal. And finally, since the locking means is inaccessible, the lock cannot be tampered with without destroying the skirt of the cap and so making it evident that something is wrong.

When the user wishes to open the package, he screws the cap down to full closed position (Fig. 2), thus puncturing the initial closure and breaking out web 46 (Fig. 2). Then he screws the cap back to open position (Fig. 3), in which position the bottle contents can flow out through openings 44 and port 45. To re-seal the package, cap 37 is again screwed down to closed position. In that position, plug 30 closes port 45 and sealing gasket 54 prevents leakage down the thread.

In the construction shown in Figs. 1-6 a right hand thread for the cap is provided. It will be understood that for a left hand thread, the direction of facing of the breakers 39 and the weakened areas 33 will be reversed.

In Figs. 7-11 there is illustrated a modification. The main differences are that the attachment is in two parts instead of one and that there is a different method of subsequent sealing. In this additional embodiment, a container 56 has a neck provided with a thread 57 like the thread previously described. Telescoping the bottle neck is a cup-shaped, internally threaded cap 58 formed of molded plastic material. In the top of the cap is a conical discharge port 59 initially closed by an integral web 60 like the web previously described. In closed position of the cap the port 59 is closed by a conical valve element or plug 61.

In packaging various liquids and other products it is considered necessary, or at least preferable, to avoid contact of the contents with aluminum, tin plate or other so-called sheet metals. The objections to such contact do not apply, however, to other materials such, for example, as pure tin (using the term to mean commercially pure tin, as distinguished from tin plate, but not necessarily chemically pure tin). To make the complete attachment, such as that shown in Figs. 1-6, of pure tin involves too great an expense and, in addition, pure tin is probably not suitable for the clamping and locking features of the attachment.

According to the present exemplification, there is provided a two-part attachment so constituted that the part which comes into contact with the container contents may be formed of one material and the part which is secured to the container of another material. These parts may, for convenience, be referred to as the closure part and the anchoring part.

As here shown as an example, the closure part (Fig. 9) comprises a ring-like body portion 65 and terminates at the bottom in an outward flange 66. Inside the body portion is a relatively flat frangible annulus 67 and the plug 61. This part of the two-part attachment, which comes in contact with the bottle contents, may be made of tin, e. g. what is known as extruded tin.

The anchoring part of the attachment, which does not come in contact with the bottle contents, may be made of any suitable sheet metal or the like. As shown (Fig. 10), it comprises a ring-like body portion 68 at the top of which is an inward clamping flange 69 which overlaps the flange 66 to anchor the end closure when the parts are assembled. Below the body portion 68 is an inward V-shaped bend 70, the lower leg of the V constituting an outwardly and downwardly flaring locking flange 71.

The exemplification of a two-part attachment illustrated in Figs. 7-10 may be constructed to be assembled with a snap-on action. To this end, the V-shaped bend 70 and the locking flange 71, which correspond to the ultimate bend and flange of Figs. 1-3, are pre-formed. The anchoring part of the attachment is split, as at 72, at a number of points around its circumference, these splits extending from the bottom edge of the locking flange through the V-shaped bend and well up into the body portion 68 (Fig. 10). Cooperating with the split attachment, the bottle has a locking ring 73. The lip of the bottle, which forms the top of the locking ring, is sloping or rounded, as appears in Figs. 7 and 8, for reasons herein-after referred to.

To enable the anchoring part of the attachment to be assembled in a predetermined angular position, the body portion 68 has an inward nib 74 which takes into a groove, like groove 42, in the locking ring of the bottle. This engagement also serves to prevent any relative angular movement after assembly. To enable the closure part of the attachment to be assembled and retained in a predetermined angular position, the clamping flange 69 has two notches 75 which receive lugs 76 formed on the closure portion.

To assemble the two-part attachment above described, the two parts are first brought together into the relation of Figs. 7 and 8, the split V-shaped bend 70 yielding to pass flange 66. Thereafter the attachment as a unit is assembled onto the bottle mouth. As the unit is applied to the bottle, the pressure of the V-shaped bend against the lip of the bottle causes the split skirt of the attachment to tend to straighten out. That is, the V of the bend widens out until the bend can slide down and over the curved or sloped bottle lip to pass the edge thereof. After so passing, the inherent resiliency of the metal causes the skirt to spring back to or towards its initial and normal position, whereby the V-shaped bend snaps in under the shoulder of locking ring 73. In this position, overlapped flanges 66, 69, are pulled down against the bottle mouth, or against a sealing gasket 77 if one is used, and the two-part attachment is secured, as a unit, to the bottle neck.

It is to be understood that the two-piece attachment may be secured in place by a spinning action instead of by the snap-on action just described. In that case, the anchoring portion is not pre-formed as to bend 70 and locking flange 71 and the splits 72 may be omitted. The two parts may be assembled together as above described, and then applied to the container as a unit, the skirt of the anchoring portion being spun in under the bottle locking rim and flared outwardly to form locking flange 71. Similarly, the one-piece attachment of Figs. 1-5 may be adapted to a snap-on assembly by pre-forming and splitting the skirt.

The cap 58 has an internal bead 78, like the bead 51, which provides an upwardly facing shoulder for engaging the locking flange 71 to prevent removal of the cap. The cap also has a recess 79 like recess 52. It will be apparent that cap 58 is assembled in the same manner as cap 37.

In connection with Figs. 1-6, there was described the feature of effecting a seal, for a once opened container, outside the openings in the initial end closure. In the modification of Figs. 7-11 this sealing is accomplished by forcing or wedging a part carried by the container neck 76 against a part of the cap when the cap is in full

closed position. This further embodiment also has means for puncturing or breaking predetermined areas of the initial end closure and the wedging and breaking elements may conveniently be combined.

In the exemplification illustrated in Figs. 7-9, annulus 67 is surrounded by an outer wall 81 which is conveniently a rim or lip formed as a continuation of ring 65. The annulus 67 is provided with a plurality, in this instance four, weakened areas 83 formed conveniently by a thinning of the metal, as appears in Figs. 7 and 9.

Extending downwardly from the top of the cap and aligned with annulus 67 is an annular wedge 84. At intervals corresponding to the number of weakened areas 83, this wedge is extended into a plurality of puncturing elements or breakers 85 generally like the breakers previously described. Surrounding this wedge and spaced therefrom sufficiently to receive lip 81, the cap 20 has a vertical abutment wall 82.

The cap 58 is initially assembled in a position short of full closed position. As in the previous embodiment, this leaves the initial end closure and the indicating web intact (Fig. 7). When it is desired to use the contents, the cap is screwed down to full closed position. During this movement, the breakers 85 puncture the weakened areas 83. While the drawings illustrate the metal as being broken away over the weakened areas 30 and curled up ahead of the breakers, it is to be understood that this does not necessarily result from the construction described. It is possible that in some cases the weakened area will be split or ruptured and pushed aside. In any event, the puncturing provides passages in the end closure for the flow of the container contents. During the end of this same movement of the cap, web 60 is broken out by plug 61. Then the cap is screwed up to open position again, thus opening 40 port 59 to permit discharge of the contents.

To reclose the container, the cap is again screwed down to full closed position. In this position plug 61 closes port 59 and the breakers enter and at least partially close the openings 45 previously formed. The wedge 84 engages lip 81 and by its wedging action forces the lip outwardly against abutment wall 82 of the cap. This wedging action, by taking up the clearance between the cap and the attachment, due to manufacturing 50 tolerances, effects a tight seal around the entire periphery of the closure outside the end passages.

In Fig. 12 is illustrated a further modification. In this embodiment certain features of the invention are shown in connection with a collapsible 55 tube such as is used for pastes, creams and the like.

As shown as an example, a collapsible tube 88 has a threaded neck 89. Formed as an integral part of the neck is an initially imperforate end 60 wall 90 having a plurality of weakened areas 91, in this instance three. These weakened areas are thinned portions of an annulus bounded by an outer wall 94 which is conveniently formed as a terminal lip on the container neck. Rising from 65 this end wall and integral therewith is a conical plug or valve element 92.

In threaded relation with the tube neck is a cup-shaped cap 102 having a conical discharge port 103. No web for initially closing this port 70 is illustrated but one may be used if desired. The cap has an annular wedge 95 extended at intervals to form breakers 96. Surrounding the wedge, and spaced therefrom sufficiently to receive lip 94, is a vertical abutment wall 98. When the cap 75

is first screwed down to full closed position the breakers break away the weakened areas 91, as previously described in connection with Figs. 7-11, to form passages for the flow of the tube 5 contents. After the cap has been opened and again closed, the breakers enter the passages to close the same and the wedge 95 forces lip 94 against abutment wall 98, taking up the clearance, to effect a seal. Carried by the tube neck 10 is a locking flange like those previously described. To this end, as here shown as an example, a short distance below the mouth of the container is an external bead 99 which may be termed a locking ring since it is analogous, for this purpose, to the 15 locking ring 73 of Figs. 7 and 8. Secured to this locking ring by a snap-on action is an attachment generally like the lower or anchoring part of the attachment shown in Figs. 7, 8 and 10 and terminating in locking flange 100. Cooperating with this 20 flange, to prevent removal of the cap, is a bead 101 on the cap similar to the beads previously described. The cap has a gasket 104 corresponding to gasket 54 of Figs. 1-3.

In the exemplifications here shown and described, the locking flanges and complementary anchoring portions of the attachments are annular. It will be understood, however, that the invention is not limited to that form and that the desired result may be obtained by one or more 25 segmental locking and anchoring elements.

In the various embodiments here illustrated, the caps and container threads are mutually engaged at all times, once the cap is assembled on the container. It is to be understood, however, that, 30 if desired, the parts may be so arranged that the cap thread disengages the container thread before the internal bead of the cap engages the locking flange on the container. With such an arrangement the threads are not in engagement when 35 the cap is in its uppermost or full open position and out of contact with the top of the initial closure element.

The invention has been described in connection with bottles and collapsible tubes but it is to be understood that the invention is applicable to 40 various kinds and types of containers.

What is claimed is:

1. In combination with a container having a neck, an initially imperforate end closure for completely closing the mouth of the container, said 45 end closure having a plurality of weakened areas, a cup-shaped cap having a threaded relation with said container neck, said cap having a discharge port in the top thereof, a plug carried by the 50 container neck for closing said port in full closed position of the cap, and means carried by the cap for rupturing the material of said weakened areas upon movement of the cap into full closed position.

2. In combination with a container having a neck, an initially imperforate end closure for completely closing the mouth of the container, said end closure having a frangible portion, a cup-shaped cap having an axial movement on the 55 container neck, means for preventing removal of the cap, said cap having a partially formed discharge port in the top thereof, an integral web initially closing said port, means carried by the cap for rupturing said frangible portion upon initial movement of the cap into closed position, and a plug carried by the container neck and arranged to break out said web upon said initial closing movement of the cap and thereafter to close said discharge port in closed position of the 60 cap.

3. In combination with a container having a neck, an initially imperforate end closure for completely closing the mouth of the container, said end closure having a frangible portion, a cup-shaped cap having an axial movement on the 65 container neck, said cap having a partially formed discharge port in the top thereof, an integral web initially closing said port, means carried by the cap for rupturing said frangible portion upon initial movement of the cap into closed position, a plug carried by the container neck and arranged to break out said web upon said initial closing movement of the cap and thereafter to close said discharge port in closed position of the 70 cap, and means for preventing complete removal 10 of the cap.

4. In combination with a container having a neck, a locking ring on said neck, an attachment secured to said locking ring and comprising an initially imperforate end closure for the container 20 mouth, said end closure comprising an annulus having a plurality of weakened areas and a central conical plug, a cup-shaped cap telescoping the container mouth and having an axial movement on the neck, and a plurality of puncturing 25 elements extending down from the cap and capacitated to rupture said weakened areas upon initial movement of the cap into closed position, said cap having a discharge port closed by said plug in closed position of the cap.

5. In combination with the threaded neck of a container, a locking ring on said neck, an attachment secured to said locking ring and comprising an initially imperforate end closure for the container mouth, said end closure comprising 30 a substantially horizontal annulus and a central conical plug, said annulus having an arcuate weakened area, a cup-shaped cap telescoping the container mouth and having a threaded relation with the neck, an arcuate puncturing element 35 extending downwardly from the top of the cap and capacitated to rupture the material of said weakened area upon a predetermined movement of the cap toward closed position, said cap having a discharge port in the top thereof arranged to 40 be closed by said plug in full closed position of the cap.

6. In combination with the threaded neck of a container, a locking ring on said neck, an attachment secured to said locking ring and comprising an initially imperforate end closure for the container mouth, said end closure comprising a substantially horizontal annulus and a central conical plug, said annulus having an arcuate weakened area, a cup-shaped cap telescoping the 50 container mouth and having a threaded relation with the neck, an arcuate puncturing element extending downwardly from the top of the cap and capacitated to rupture the material of said weakened area upon a predetermined movement 55 of the cap toward closed position, and means for attaining and maintaining a predetermined angular position of said attachment on the container neck, said cap having a discharge port in the top thereof arranged to be closed by said 60 plug in full closed position of the cap.

7. In combination with the neck of a container, an initially imperforate end closure for completely closing the mouth of the container, said end closure comprising an annulus having a plurality of weakened areas and a central conical plug, a cup-shaped cap telescoping the mouth of the container and having an axial movement on the 70 neck, said cap having a discharge port in its top arranged to be closed by said plug in full closed 75

- position of the cap, means carried by the cap for rupturing the material of said weakened areas upon the initial movement of the cap into closed position, thereby to form openings for the passage 5 of the container contents, and means for subsequently effecting a peripheral seal outside said openings when the cap is in closed position.
8. In combination with the neck of a container, an end element extending across the container 10 mouth and having a substantially horizontal portion bounded on the outside by an annular lip, said portion having an opening for the passage of the container contents, a cap telescoping the container mouth and having an axial movement on said neck, an annular wedge extending downwardly from the cap above said portion, and an abutment wall on said cap spaced from said wedge and defining a recess capacitated to receive said lip, the parts being so arranged that 15 said wedge forces said lip against said abutment wall in closed position of the cap, thereby to effect a peripheral seal outside said opening.
9. In combination with the neck of a container, an end element extending across the container 20 mouth and having a conical plug surrounded by a substantially horizontal annulus, an upstanding lip bounding said annulus on the outside thereof, said annulus having an opening for the passage of the container contents, a cap telescoping the container mouth and having an axial 25 movement on the neck, said cap having a discharge port arranged to be closed by said plug in closed position of the cap, an annular wedge extending downwardly from the cap above said 30 annulus, and an abutment wall on said cap spaced from said wedge to receive said lip, the parts being so arranged that said wedge forces said lip against said abutment wall in closed position of the cap, thereby to effect a peripheral seal outside 35 said opening.
10. In combination with the neck of a container, an initially imperforate end closure for the container mouth, said end closure having a frangible portion, an upstanding lip bounding 40 said portion on the outside thereof, a cap telescoping the container mouth and having an axial movement on the neck, an annular abutment wall on the cap, and means carried by the cap for rupturing said frangible portion upon initial 45 movement of the cap into closed position, thereby to form an opening for the passage of the container contents, and for wedging said lip against said abutment, in closed position of the cap, thereby to effect a peripheral seal outside said 50 opening.
11. In combination with the neck of a container, an initially imperforate end closure for the container mouth, said end closure having a frangible portion, an upstanding lip bounding 55 said portion on the outside thereof, a cap telescoping the container mouth and having an axial movement on the neck, an annular wedge extending downwardly from the cap above said portion, part of said wedge being extended downwardly 60 to form a puncturing element for rupturing said portion upon a predetermined movement of the cap toward closed position, thereby to form an opening for the passage of the container contents, and an annular abutment wall on said cap 65 surrounding said wedge and spaced therefrom to receive said lip, the parts being so arranged that said wedge forces said lip against said abutment in closed position of the cap, thereby to effect a peripheral seal outside said opening.
12. In combination with the neck of a container, 70 a locking ring adjacent the mouth of the container, an initially imperforate end closure for the mouth of the container having a frangible portion, an anchoring attachment secured to said locking ring, inter-engaging parts on said end closure and anchoring attachment for securing the end closure in position, a cup-shaped cap telescoping the container mouth and having an axial movement on said neck, and means on said cap for rupturing said frangible portion upon a predetermined initial movement of the cap toward closed position.
13. In combination, a container having a threaded neck, a locking ring on the neck adjacent the mouth thereof, an initially imperforate end closure for the mouth of the container having a weakened area, an anchoring attachment secured to said locking ring, inter-engaging parts on said end closure and anchoring element for securing the end closure in position, means for attaining and maintaining a predetermined angular position of the attachment on the container neck, means for attaining and maintaining a predetermined angular position of the end closure with respect to the attachment, a cup-shaped cap having a threaded relation with the container neck, and means on said cap for rupturing the material of said weakened area upon a predetermined initial movement of the cap toward closed position.
14. In combination, a collapsible tube having a neck, an initially imperforate end closure formed integral with the neck and having a frangible portion, a cup-shaped cap having an axial movement on said neck, said cap having a discharge port in the top thereof, a plug integral with said end closure for closing said port in full closed position of the cap, means carried by the cap for rupturing said frangible portion upon initial movement of the cap into closed position, thereby to form an opening for the passage of the container contents, means for effecting a peripheral seal outside of said opening when the cap is in closed position, and means for preventing complete removal of the cap.
15. In combination with a container having a neck, an initially imperforate end closure for completely closing the mouth of the container, said end closure having an area bounded on three sides by weakened or scored lines, a cap having a threaded relation with the container neck, an element on said cap for engaging said area upon a predetermined movement of the cap into closing position, whereby a tongue of metal is ruptured from the end closure but is left rooted thereto, means for preventing removal of the cap, and means operable upon said movement of the cap for altering the external appearance thereof.
16. In combination with a container having a neck, an initially imperforate end closure for completely closing the mouth of the container, said end closure having a frangible portion, a cup-shaped cap having an axial movement on said neck, said cap having a discharge port in the top thereof, a plug carried by the container neck for closing said port in full closed position of the cap, and means carried by the cap for rupturing said frangible portion upon a predetermined movement of the cap toward closing position.
17. In combination with a container having a neck, an initially imperforate end closure for completely closing the mouth of the container, said end closure having a frangible portion,

cup-shaped cap having an axial movement on said neck between an open and a closed position, said cap having a discharge port in the top thereof, a plug carried by the container neck for closing said port in full closed position of the cap, means for limiting the axial movement of the cap toward open position and preventing its removal, and means carried by the cap for rupturing said frangible portion upon the initial

10 movement of the cap into closed position.

18. In combination with a container having a neck, an initially imperforate end closure for completely closing the mouth of the container, said end closure having a frangible portion, a 15 cup-shaped cap having an axial movement on said neck between an open and a closed position, said cap having having a frangible portion, means for limiting the axial movement of the cap toward open position and preventing its removal, 20 means carried by the cap for rupturing the frangible portion of said end closure upon initial

movement of the cap into closed position, and means for causing the frangible portion of the cap to be ruptured upon said initial movement.

19. In combination with a container having a neck, an initially imperforate end closure for completely closing the mouth of the container, said end closure having a frangible portion, a cup-shaped cap having an axial movement on said neck, said cap having a discharge port in the top thereof, a plug carried by the container 10 neck for closing said port in full closed position of the cap, means carried by the cap for rupturing said frangible portion upon a predetermined movement of the cap toward closing position, and means for effecting a peripheral seal, 15 outside the opening formed by the rupturing of said frangible portion, when the cap is in closed position.

BRENT F. CAHOON.

HOWARD C. SEAMAN, JR. 20
